APPARATUS FOR REMODELING LASTS

John D. Owen, Stoughton, Mass.

Application December 2, 1936, Serial No. 113,816

6 Claims. (Cl. 144—278)

This invention relates to improvements in apparatus for remodeling lasts.

More particularly it relates to the remodeling of a last by substituting a new forepart.

5 Changes of styles in shoes entail heavy expense because lasts which are sound and mechanically good have to be discarded. It has long been recognized that large economy would result, if a practicable way were known for 10 changing the forepart of a last.

Proposals to make lasts with detachable foreparts and a plurality of substitute foreparts have not won general acceptance, because mechanical fastenings become loose; and because style 15 changes occur, unforeseen; and because of various other objections.

Proposals to remodel integral lasts have been by substituting a rough block for a severed forepart and then, with the block secured to the residue of old last, turning the block to the desired new shape of forepart. This procedure has proved unsatisfactory for various reasons, including the inability to mount in a lathe, because of the absence of old centers, and the extreme difficulty of shaping the new forepart precisely to 20 desired contour without shaving or otherwise removing stock from the adjacent residue of the old.

The present invention starts with a last in 25 which the body and toe are one integral piece, actually or in effect. This may carry such surface plates as may be wanted; and the body and heel may have whatever hinge, or block, or other arrangement may be preferred for extracting the last from the shoe. In the remodeled last which 30 the invention provides, the connection of toe to body is integral, in the practical sense of being permanently rigid and secure, although the toe is in fact a separate piece of wood fastened to the body.

40 It is a characteristic of the present invention that the new forepart and the old body part fit together with perfect joinder of adjacent surfaces, without any wastage of material of the body, notwithstanding the difficulties above mentioned, arising from absence of turning centers and from diverse settings in the lathe of manufacture and the lathe of the remodeling.

45 Since the remodeling is effected without the old body having been made initially attachable and detachable, with respect to the forepart, it is an advantage of my invention that it can be applied to any of existing millions of ordinary wood lasts (assuming the old body to be adequate), 50 with the effect of converting an old last of no

value into a new one at not much more than the cost of making the new fore portion. And this can be repeated an indefinite number of times. It is assumed in each case that all of the desired remodeling can be expressed in the fore portion— 5 which is usually the fact. The place for severing toe from body can be selected as far back from the tip as may be necessary in order that the severed fore portion shall include all of the places where the contour of the last is to be changed, 10 provided, of course, that it be forward of the hinge, if any, so that the saw does not find metal in its line of cut. Outside plates, if any, can be removed for the sawing, and replaced. The new part which is to replace the severed portion may 15 be longer or shorter, wider or narrower, thicker or thinner, made with more spring, or more swing, or less of either, and may embody any variations in other respects as if the new fore part were an integral part of a new entire last. 20 The special sawing of the forward end of the body, and sawing of the rear end of the forepart, make the smooth joinder of their respective contours.

To attain these ends the invention uses customary methods for the rough-turning and shaving of a new forepart, starting with a rough block having only the length of the forepart with slight excess. The shaving leaves the block devoid of the toe-stub that carried the forward "center" 30 on which the block was turned; and leaves it in the desired final shape; and practically in the desired final size, for the subsequent scouring and polishing takes off only about a quarter of a size, which does not affect its fit to the body part. 35

The invention provides for the determining of a proper length for the residue to be retained of the old last, and a proper length for the replacement forepart, in order that the remodeled last shall be of desired length; and provides for a 40 quick and perfect fitting of these two together. This latter is done by sawing each, at a place where it is identical with the other in shape; effecting this sawing on cylindrical surfaces, that on each being identical with that on the other in curvature; and if desired by marking guide points, one on the residue of body, and one on the new forepart, while they are separate, at their 45 cylindrical surfaces which are to go together. The putting of the two guide points together 50 when those surfaces are together will guide the setting of the forepart with correct swing with respect to the body part. This marking is optional, being sometimes useful but not really necessary in practice. 55

It will be understood that, in cases to which the invention applies, the master model for the remodeled last can be made from one of the old lasts in the manner customary by adding layers of material to it to build up a fullness, or shaving material from it, so as to convert it to the desired new shape, according to the art of a model-maker. When a rough block is put into a lathe and a forepart is turned, with that remodeled shape as a guiding master model, the rear portion of the forepart, at and back of the place for its fitting to the body part, will have a region identical in shape with the corresponding region of the master model, and therefore identical in shape with the corresponding region of each of the old lasts which are to be remodeled. The old last which is to be remodeled is therefore cut off in this region, on a cylindrical surface; and the severed forepart is discarded. This may be done by a band saw, with the last mounted on a swinging work table. The new rough-turned-and-shaved forepart is severed in its corresponding region, its excess length being cut off at a proper distance from the fore-tip (according as the new toe is to be longer or shorter); and the severed rear portion of the forepart is discarded. This cut may be made by the same band saw, making a cylindrical surface with the same radius of table except that the radius is preferably reduced by the thickness of the saw cut. The identity of contour shapes at the regions where these cuts are made permits of the old body and the new forepart being put together with perfect and firm fit of their cylindrically cut surfaces, and with practical identity of external contour.

The region for effecting this union may for brevity be referred to as a "mid-region" of the last. It is aft of all forward regions where any contour is to be changed; and it is forward of the rear and main body portion of the last, containing the hinge and principal metallic obstacles to the making of a saw cut. There will ordinarily be ample length of space here where the contour of the old last is not to be changed, and where, therefore, each one of the old lasts will be like all the others of the same style in contour; and any one of them can be chosen to be that one which will be altered by hand to become the pattern or model for the new.

These steps are accomplished by ascertaining and recording in a cradle a known position of the old last, and severing its forepart on a surface having a known relation to that position; and, if desired, recording on the residue a point showing its relation to the said position; setting the new forepart in its appropriate portion of that same position, this having previously, in an operation by itself, been prepared in the desired new shape, with a small excess length of mid-region of the last; cutting off the excess at its rear, to a surface occupying the same relation to that position as did the forward surface of the body, at which the last was severed; recording on the forepart, if desired, a point having a known relation to the said position; and putting the surfaces of severance together, of the residue body and the residue forepart, with their recording points indicating the proper relation of these residues to each other for reproducing in their assembly the relation which each separately held with respect to said known position of the whole last when it was set therein.

In practice these steps may be accomplished thus: First, setting the old last into a holder or 75 jig, having adjustable points for support and for

positional touch of the old last, and holding the last therein on a band saw table which swings for the forepart to be cut off on the said cylindrical curve, and if desired, recording the said guide point by a mark on it, showing its position relative to the jig. Second, setting the previously turned and shaved forepart into the same jig, the forward points of which for support and touch have been adjusted slightly for the oversize and for any change of size, or further change of swing or spring that may be desired or for any contour change which occurred at points of contact of the jig with the new forepart; and swinging the forepart across the saw to remove its rear excess length on the same said cylindrical curve, 15 the relation of table to saw having been adjusted for the thickness of previous saw cut; and if desired, marking on the forepart, at or near said cylindrical surface, a record point which is at the same location, relative to the jig, which was 20 marked on the body residue of last. Third, setting the body residue of last back into the jig for the fitting together of the old body and the new forepart.

While they are thus fitting together they can be compared with the pattern, adjusted on their cylindrical arc bearing, if desired, and then secured together, as by glue and pressure, and by sunken screws and dowel pins, so as to make a solid last in which, for all practical needs of a 30 shoe factory, the forepart is as if it were integral with the body part. That body part may be of the hinged type or otherwise as may be desired.

The finishing of the forepart may then be completed as in the case of a solid last, by scouring, 35 polishing, dipping, and by adding a toe-iron if desired. As the smoothing of the rough finish by the scouring reduces the forepart only about a quarter of a size, it is clear that the perfecting of the smoothness of joinder of surfaces involves 40 no violating of the original form at this region of identity, as the forepart there is already in practically its final form. When put together the shape of each at the cut fits the other precisely; and the pre-existing shape of the body part does 45 not need to be violated in making a smooth joinder.

It results therefore that the remodeled last requires only the labor for making and affixing the new forepart, with no spoilage of the body 50 portion, and with a great saving over previous methods.

While the invention can be performed with the greatest assurance as to precision of execution by use of the apparatus herein described, or its 55 equivalent, this apparatus is not essential. In place of the described position recording means and positioning means by contact barriers and supports, the skill and strength of a proficient band saw operator can set and guide the last and 60 the element that is to constitute the new forepart—particularly if he be aided by marks on the carrier plate against which he can sight while holding these parts for the sawing.

Also, while the severing of the old last and the 65 trimming of the rear of the new forepart for making the union are best performed by making cylindrical surfaces to fit together, as by a band saw or other saw which can cut on a circle, this severing can be done on other lines. The great 70 advantage of having cylindrical surfaces for the joinder is that the fitting of the curves together automatically sets the new forepart at a correct angle to the body, without canting either to right or left. This is useful when they are to be held 75

in hand for the securing together. However, this correctness depends upon the correct cradling of the new forepart in the jig. If the parts are to become secured together while both are correctly set in the jig; or if their correct relations to each other are to be then indicated by marks on each, or otherwise, the curvilinear nature of the surfaces of severance and of union can be dispensed with, and the saw cut can be on other lines according to convenience. In particular a travel of saw straight across can be substituted, such as the customary straight feed of work past a circular saw, which can cut only a plane surface.

It is intended that the patent shall cover, by suitable expression in the appended claims, whatever features of patentable novelty exist in the invention disclosed.

In the accompanying drawings:

Figure 1 is a top plan of a device, embodying features of the invention, suitable for practicing my improved method of remodeling lasts. A curved dot and dash line indicates a last which is to be remodeled, set in position where its fore part is partly severed from the body part;

Figure 2 is a top plan of the under supporting plate or bed, showing the combined slide and hinge by means of which the last-holder or carrier plate is variously shiftable and adjustable on the bed;

Figure 3 is an elevation, in section on 3—3 of Figure 1;

Figure 4 is an elevation, in section on 4—4 of Figure 1;

Figure 5 is a view similar to Figure 1, but with a new pre-modeled forepart of last indicated by dot and dash lines; and a second position of the carrier plate indicated also by dot and dash lines;

Figure 6 is an elevation, in section on 6—6 of Figure 5;

Figure 7 shows a conventional type of last whose forepart has been cut from the body part according to teachings of the invention;

Figure 8 is an elevation of a new and independently modeled forepart of last prior to removal of surplus stock at its butt end;

Figure 9 is a view similar to Figure 8 showing the surplus at the butt end cut away, according to the invention, from the pre-modeled forepart;

Figure 10 shows the pre-modeled forepart of Figure 9 joined to the preserved main body of last which is seen in Figure 7;

Figure 11 is an elevation, in section as if on line 3—3 of Figure 1, but of a modified form of device wherein a last or forepart may be sawed obliquely with respect to the longitudinal axis of the last or forepart;

Figure 12 is an elevation of a last with its forepart severed according to the disclosure of Figure 11;

Figure 13 is an elevation of a completed remodeled last;

Figure 14 is an elevation of a woman's shoe last, its forepart being severed in obliquity to the longitudinal axis, the obliquity being opposite to that of Figure 12, as if cut on a device having a carrier plate corresponding to that of Figure 12 but pivoted near its rear end, for tilting forward;

Figure 15 is an elevation, in medial longitudinal section, of a device for assembling an old rear part and a new forepart; and

Figure 16 is a top plan of the device of Figure 15.

Referring to the drawings, the apparatus por-

trayed in Figures 1—6 comprises the two main parts 10, 12 which for convenience will be referred to herein respectively as the bed plate and the carrier plate. The bed plate 10 may be secured, as by the screws 14, on the top of a work table 16, of a band saw, which plates have a slot 18 running inward from that edge toward which the work swings while being fed to the saw. This slot extends well beyond the location of the saw 20, for enabling initial proper positioning of the plate relative to the saw.

The carrier plate 12 is mounted on the bed plate, but its only connection to the bed plate is through a bar 22 which is slidably engaged in a dovetail groove 24 in the bed plate. One end portion 22' of this bar is hinged to the other portion 22'' on a vertical axis 26 (Fig. 2); and the carrier plate 12 is rotatably connected to the bar portion 22' as at 28, so that the carrier plate, in addition to being rotatable on the pivot 28 is shiftable over the surface of the bed plate by movement of the bar portion 22' in its groove 24. A quadrant depression 30 (Figure 2) in the midst of top face of the bed plate, permits swing of bar portion 22' from and to alignment with the bar portion 22'', one limiting wall of the depression being a precise continuation of a wall of the dovetail groove 24 against which the bar portion 22' slidably engages in its said alignment with bar portion 22''.

The bar 22 is adjustable along groove 24 by means of screw 32 whose threads engage in fixed plate 34 at the edge of the bed plate 10. And a knurled finger piece 36 at the end of screw 32 facilitates the adjustment in conjunction with a suitable scale 38 whose utility will later appear.

Carrier plate 12 has a relatively large recess or broad slot 40, running in from that side edge toward which the work is fed, within which slot the saw is located, preferably, in all positions of the plate 12. The slot 40 has breadth and shape sufficient to permit the necessary movements of plate 12 without any portion of it coming against the saw. Thus plate 12, for the act of placing a last therein, may be swung from its position of Figure 1 to the dot and dash position of Figure 5, in which case the movement breaks the rectilinear setting of bar 22 on its hinge 26 as indicated by dot and dash lines in Figure 2. This puts the plate 12 in a position where the saw 20 stands at or adjacent to the wide entrance to slot or recess 40. After the last has been properly placed and adjusted on plate 12, as will hereinafter appear, the plate 12 may be swung back until bar portion 22' is in rectilinear alignment with bar portion 22''. Then the plate 12 may be rotated slowly on pivot 28 to bring the work against the saw 20 as seen in Figure 1. I prefer to provide stop means, such as pins 42, 44, for preventing accidental movement of plate 12 against the saw.

Further important features of the invention reside in cradling means for mounting and accurately adjusting the work on the carrier plate 12, so that the cutting of a forepart from an old last, and the cutting of a pre-modeled new forepart, may be accomplished in such a manner that the main part of the old last and the pre-modeled new forepart will be combined with required accuracy and nicety of fit of one to the other—as distinguished from prior practices where the new forepart has been put on as a block that had to be subsequently modeled and made to fit the old body.

According to the invention, a heel rest 46 is secured to a vertical slide 48 which is vertically adjustable in a rear barrier 50. And barrier 50 is adjustable along carrier plate 12 by being mounted on the spread runners 52, 52, each of which is slidably engaged in a dovetail-groove way 54. However, when the barrier 50 has been set initially in a desired position on carrier plate 12, it may be locked there by the lock screw 56, 10 which may be similar to the device shown in detail in Figure 6.

The rest 46 and its slide 48 constitute a unit which may be clamped at various elevations on barrier 50. For this, a screw 58 is fixed on slide 15 48 and projects through a vertical slot 60 in barrier 50. And a clamping nut 62 is threaded on the end of screw 58 for engaging the barrier and clamping the slide and barrier against relative movement.

20 The unit 46, 48 may be raised or lowered by taking hold of it and thrusting it up or down while the clamp 62 is loosened. But I prefer to provide a means for fine vertical adjustment of the unit, such as the screw 64 threaded through rest 46, with its inner end movable into engagement with plate 12, and with its outer end accessible for adjusting the screw, thereby to adjust the unit 46, 48.

When an old last is to be mounted in the device, it will be set on rest 46 with the back of its heel portion thrust against slide 48, as seen in Figures 1, 3. In order to center it, and to retain it at this rear location, I provide the laterally adjustable lugs 66, 66 and 67, 67 for engaging the heel portion of the last at two spaced locations at opposite sides. Each pair of lugs may be threaded on a right and left screw 68, centrally anchored at 70, on rest 46, against lateral movement. The lugs are slideable and non-rotatably mounted, so that rotation of a screw 68 in counter-clockwise direction in Figure 1 would cause the lugs 66, 66 or 67, 67 to engage the last the more tightly from opposite directions, the simultaneous movements of the lugs toward the center line of plate 12 ensuring accurate centering of the rear portion of the last.

50 The support for the forepart of the last is provided on the other side of groove 40, so that the saw 20, working along the slot 40 as plate 12 is swung toward the saw, passes between the forward and the rear supports for the last, and severs the forepart from the main body. The forward support includes the laterally adjustable pieces 72, 72 for engaging under the last a little forward of the ball of the last, each piece 55 72 having a vertical extension 72' with curved lateral face for engaging a side of the last. The pieces 72, 72 are shown fixed as to elevation; and their extensions 72', 72' are comparable to the lugs 66, 66 or 67, 67 at the rear, being simultaneously movable toward and away from their respective sides of the last by means of the right and left screw 74.

Toward the toe of the last, I provide similar 65 laterally adjustable pieces 76, 76, each having a vertical extension 76, for engaging a side of the last at this region. Both of these sets of pieces 72, 72 and 76, 76 may have their lateral adjustment each in a slide which itself is adjustable laterally by means of an adjusting screw. I show such a slide 73 for the pieces 72, 72, and one 78 for the pieces 76, 76, with their respective adjusting screws 75, 80. By this means I provide for accommodating different shapes and styles 70 of toe. A scale 77 on plate 12 facilitates proper

adjustment of both sets of pieces 72, 72 and 76, 76.

The pieces 76, 76 are resiliently mounted to yield vertically for accommodating different degrees of toe-spring. For this purpose each piece 5 76 may be backed by a spring 82; and each may have a set screw 83 for holding it at a proper elevation. If desired the pieces 72, 72 may be adjustable vertically the same as pieces 76, 76.

A forward barrier 84 has the side runners 86, 10 86 engaged in the dovetail groove ways 88, 88 in plate 12, permitting the barrier to be moved against the tip of the toe of the last. And the barrier may be locked in its adjusted position by a screw lock 90, as shown in detail in Figure 15 6. This barrier 84 conveniently may carry the adjustable last-tip rest 85 which may be set with regard to a scale 87 for engaging under the tip of a last of known toe-spring.

I find it desirable also to provide a mid-support 20 for the last, although the forward and rear supports will be formed sufficient in most cases. The mid-support 92 may be moved along its way 94, for standing under the mid-portion of a complete last, or under the stub end of a new fore- 25 part of last, to assure against movement of the residue against the saw, after the saw has severed a forepart from that residue.

It is a feature of the invention that the setting 30 of rear and forward barriers 50, 84 results in a simultaneous setting of scale elements for indicating the stick-length of last. Conveniently the scale elements 96, 98 may be carried, one by a runner 52 of barrier 50, and the other by a runner 86 of barrier 84. And these scale elements 35 extend side by side in way 54, 88, which join each other to provide a continuous way for the purpose. As portrayed, one scale element may be graduated for coaction with a mark on the other, to indicate stick-length sizes of lasts.

The method of the invention can be practiced by means of the particular apparatus portrayed in Figures 1-6:

A location on an old last having been determined, back of which no change is required in the making of the desired remodeled last, the operator will set the rear barrier 50 on plate 12 approximately in position to effect a cut at that location, and will lock it there by lock-screw 56. Then the old last may be set into the device while plate 12 is in the dot and dash position of Figure 5. The heel of the last will be thrust against the slide 48 of barrier 50; and the lugs 66, 66 and 67, 67 will be brought against opposite sides of the heel by means of screws 68, 69, thereby to center the rear portion of last on carrier plate 12.

At the forepart of the last, the vertical extensions 72' 72' of the support pieces 72, 72 will be similarly brought against their respective sides of the last, the forepart meanwhile resting on the pieces 72, 72. Next the pieces 76, 76 are adjusted so that their extensions 76' 76' may engage opposite sides of the last. The adjustment of pieces 72' 72' and 76' 76' may involve a lateral shifting of the slides 73 or 78 before the extensions 72' 72' or 76' 76' engage the last. The pieces 76, 76 will automatically adjust themselves against the under toe part of the last, and may be locked there by the lock screws 83, 83. The forward barrier 84 next will be adjusted against the toe of the last, and may be locked by the screw lock 90; the scale elements 96, 98 being thereby automatically set to indicate the stick-length size of 75

the last. The mid-support 92, if desired, may be moved to a mid-supporting position.

The old last being now properly centered and cradled on plate 12, in position recorded by the set and locked position of the various contact lugs, pieces and barriers of the cradle on plate 12, the adjustment of the last, so that the saw will cut it at the predetermined location, may be accomplished by the screw 32, by means of which carrier plate 12 may be moved along the bed plate 10. Then carrier plate 12 may be swung toward the saw until the hinged bar 22' comes into rectilinear alignment with bar portion 22", after which plate 12 may be slowly rotated on its pivot 28 to feed the work against the saw, and so to sever the forepart from the last on a surface curving around the axis of pivot 28.

In Figure 7 an old last is shown, with its forepart A severed from the main body of the last B, the vertical extent of the surfaces of severance being approximately perpendicular to the longitudinal axle of the last.

A new forepart of last, which is to be put on the old body part B, is shown in Figure 8 at C, pre-modeled in the desired new form and style. This new forepart C will have been modeled in accordance with the design and style of the forepart of a master last or model which embodies the desired changes from the old. If the size of the master last is the same as that which is being remodeled, the master may be mounted in the device, as heretofore explained in connection with the mounting of the old last, to get a proper setting of the forward supports. Then the master last may be removed, and the new forepart inserted in the forward supports, which thus have been properly and accurately centered and adjusted to receive it. A slight loosening of the support pieces 72', 72", and 76' and 76" is permissible during the substitution, without danger of upsetting the adjustment.

However, it frequently happens that a complete master last or pattern is available in only one size, in which case it becomes necessary to make suitable adjustments for the making of other sizes, or for other stick lengths. All three of the scales 71, 87 and 96, 98 may be utilized in making such adjustments. Needed adjustments of stick length usually are distributed equally at toe and heel, so that one half the increase or decrease is accomplished by adjustment of the rear barrier 50, and the other half by adjustment of the forward barrier 34. Similarly the needed adjustments of pieces 72, 72 and 76, 76 may be accomplished by predetermined adjustments of their respective slides 73, 78 along the scale 77. Also the tip rest 85 may be adjusted with reference to scale 87 to attain a desired toe spring.

If a particular setting of elements accommodates a right last, or a right forepart of last as seen in Figure 5, it will be obvious that a corresponding setting of slides 73, 78 to the other side of zero on scale 77 will accommodate a left last or forepart. In Figure 5 it happens that slide 73 is set at zero, so that no adjustment of it would be required in setting for a left forepart.

With the new forepart C properly mounted on plate 12, an adjustment must be made to allow for the width of the saw cut, in order that the radius of curvature of the cut surface on the forepart will be precisely equal to the radius of the cut surface on the residue body portion B of the old last. The adjustment in any particular case will depend upon the width of cut made by the particular saw used. Usually this will be found

to be approximately one-sixteenth of an inch. Therefore, the operation should adjust carrier plate 12 this one-sixteenth of an inch, or whatever distance is proper, along bed plate 10 in direction to shorten the radius of the cutting curve that amount. The adjustment may be accomplished by screw 32, the associated scale 38 being provided to assist the accuracy of this adjustment.

The mentioned allowance for width of saw cut may be made prior to mounting the new forepart in the device, if preferred.

The act of cutting the stub end from the new forepart will be similar to the previously described cutting, after which the new forepart C and the old main part B are ready to be joined together.

Instead of the cutting, as heretofore described, having its straight line elements (the course of the saw) perpendicular to the longitudinal axis 20 of the last, or forepart, which is undergoing treatment, the cutting may be oblique to the said axis; and at present I consider this latter style of cutting preferable because it facilitates the effective joinder of a new forepart with an old body. 25

Figure 11 illustrates how this oblique cutting may be accomplished by introducing an intermediate plate 11 between the bed plate 10 and the carrier plate 12; and by hinging plate 12 near one end of intermediate plate 11, with plate 12 30 upstanding obliquely above plate 11 and adjustable in standard 15, to set the angle of saw cut. Plate 12 may be held aloft parallel to plate 11 while the work is being mounted thereon, as by the strut 17; and may then have its end dropped 35 to the full line oblique position of Figure 11 for the cutting, being held firmly against plate 11 during the cutting. Suitable means (not shown) may be provided for holding plate 12 against plate 11. If desired an extra clamp 19 may be employed in this case for holding the forepart of last. 40

In this case of oblique severance, plate 11 receives the pivot pin 28 of hinged bar 22, and is movable and rotatable the same as has been described for plate 12 in the embodiment of Figures 1-6. Carrier plate 12 rides on plate 11, so that the work is adjusted and moved to and from the saw the same as has been described in connection with Figures 1-6. 50

A last severed according to the portrayal of Figure 11 is shown in Figure 12. Figure 14 shows a last cut with opposite obliquity of severance, as if cut on a device similar to Figure 11 but with plate 12 hinged near its rear end. 55

The joining and securing of shank and pre-modeled forepart may be accomplished by using suitable glue on the cut surfaces, and pressing them together with pressure sufficient to squeeze out all but an infinitesimal film of the glue, while the parts of last are held with their cut surfaces accurately in register. When the glue has set sufficiently, or simultaneous with the application of pressure, one or more screws may be driven across the surface of joinder to make the union 60 definitely secure. 65

Figure 13 shows a complete remodeled last, with countersunk screw hole, and with a wooden pin in the countersink, concealing the screw.

This joining of parts of the last may be accomplished in the device on which the parts were cut; or may be accomplished in a special device for that purpose. 70

In Figures 15, 16, there is portrayed such a special device comprising a plate 100 on which are 75

mounted heel and toe pieces which may be similar to the pieces 66, 66; 72, 72 and 76, 76 of Figures 1-6 and 11, so that the two parts of last which are to be joined may be mounted on plate 100 in precisely the same positions they would assume in the cutting device. An adjustable under-support 102 is provided for engaging under the toe part adjacent to its cut surface. And a screw press 104 straddles the last, and may have a presser face composed of a relatively thick body of resilient material, so that, as it engages a surface of last, it tends to conform to the particular surface engaged, thereby transmitting applied pressure without injuring or defacing the last. A hole or slot 106 in plate 100 provides for drilling a hole across the surface of joinder, entering from the bottom; and for driving a screw 108, which completes the securement. A wood dowel 110 may cover the head of the screw and permit a smooth finishing of the last at this region.

The remodeled last requires no trimming to make the forepart fit the body part, because the invention has made these parts to fit precisely. Any desired scouring and polishing may be accomplished without objectionable effect.

In Figures 1, 3 and 5 there is indicated a last marking device 112 fixedly pivoted at 114 on carrier plate 12, and movable into engagement with a portion of last adjacent to the line of its saw cut. The marking device 12 may have a suitable pointed element 116 pivoted at its free end and capable of making a mark on the residue of old last and on the new forepart, to facilitate proper and accurate assembling of these parts, by bringing the said marks into registration with each other.

I claim as my invention:

1. Apparatus for remodeling lasts, comprising a saw combined with a jig, having a rear holder and a fore holder respectively for the rear part and forepart of a last; said saw and jig being relatively movable for the saw to pass through a path crossing between the rear holder and the fore holder; and means for relative adjustment of the saw and jig transversely of said path, sufficiently to set them for another passing of the saw in which that edge of path which is nearer to the fore holder will be positioned at that edge of the path of the saw's first passing which is more remote from the fore holder, thereby to provide for the cutting of a new forepart having length containing compensation for that part of the length of last which became lost by being in the path of saw-cut through the old last.

2. Apparatus for remodeling lasts, comprising a last-holder combined with a saw; said holder having a cross passage along which said saw is adapted to operate, and having last-engaging means on both sides of the passage; said engaging means on one side of the passage being adequate, without aid of engaging means located on the other side of the passage, for positioning a new fore-part of last to be trimmed by the saw so as to replace an old fore-part cut off by that saw, and so as to fit the cut face of the old rear-part from which the old fore-part was cut by that saw; and means for adjustment of the saw and holder relative to each other in the fore

and aft direction of the last for selecting the location, on said portion of last, where said cutting off is to occur.

3. Apparatus for remodeling lasts, comprising a band saw; a support; a jig pivotally mounted on the support for the severing of the fore-portion from the rear-portion of a last, said jig having an opening for travel of the saw relative to the jig across the position of a last on the jig; and last-engaging means on the jig, comprising a group of devices located on one side of the travel opening for engaging both sides and the end of one end portion of the last, and a group of devices located on the other side of the travel opening for engaging both sides and the end of the other end portion of the last; the two said groups being arranged to hold between them the whole last for said severing; and one of said groups being capable of positioning a pre-modeled fresh portion of last for being trimmed by the saw; and means for adjusting the position of this group and the pivot, relative to the saw, by moving the pivot and the saw relatively to each other a distance equal to the width cut out in said severing, so that the saw's path in said trimming of this fresh end portion will be of the same curvature as the surface which the saw in the said severing left on the complementary portion of last.

4. Apparatus for remodeling lasts, as in claim 3, further characterized in that there is a guide and therein a slide carrying the said pivot, which slide is shiftable for moving the pivot toward and from the saw in the direction of length of the last, and is a two-piece bar whose pieces are hinged together; one of those pieces and the hinge moving only at the guide, and the other of those pieces, hinged to the first, and carrying the said pivot, being movable away from the guide and from the saw.

5. Apparatus for remodeling lasts, comprising a support and a jig having means for mounting and positioning a portion of last; said jig comprising a base pivotally mounted on the support, and a last-carrier mounted on said base and hinged thereto on an axis for tilting the last relative to the line of action of a saw; said carrier having said mounting and positioning means, and there being an opening in the carrier across which the mounted last extends; and said saw, arranged for travel across the tilted last-position when said jig as a whole is moved about said base pivot.

6. Apparatus for remodeling lasts, comprising a support and a jig having means for mounting and positioning a portion of last; said jig comprising a base pivotally mounted on the support, and a last-carrier mounted on said base and hinged thereto on an axis for tilting the last relative to the line of action of a saw; means for holding said carrier at different angles of inclination, said carrier having said mounting and positioning means, and there being an opening in the carrier across which the mounted last extends; and said saw, arranged for travel across the tilted last-position when said jig as a whole is moved about said base pivot.

JOHN D. OWEN.
